UNITED STATES PATENT OFFICE.

SVEN GUSTAF WINGQUIST, OF GOTENBORG, SWEDEN, ASSIGNOR TO AKTIEBOLAGET SVENSKA KULLAGERFABRIKEN, OF GOTENBORG, SWEDEN, A CORPORATION OF SWEDEN.

MACHINE FOR MANUFACTURING TOOTHED WHEELS, SCREW WHEELS, OR THE LIKE.

Application filed March 2, 1921. Serial No. 449,008.

To all whom it may concern:

Be it known that I, SVEN GUSTAF WINGQUIST, a subject of the King of Sweden, residing at Gottenborg, in the Kingdom of Sweden, have invented new and useful Improvements in Machines for Manufacturing 5 Toothed Wheels, Screw Wheels, or the like, of which the following is a specification.

This invention relates to machines for manufacturing toothed wheels, worm wheels, bevel gear wheels or the like by milling, planing, or grinding operations according to the rolling principle or according to another generating principle in which the 10 wheel blank and the tool perform a relative rolling or rotating movement during the operation. The invention relates more particularly to such machines of the said kind in which the said rolling or rotating movement is controlled by a link system. The 15 essential inconvenience of machines as heretofore known, having motion transmitting means of the said kind, consists in this that one and the same machine cannot be used 20 for manufacturing wheels having different pitch or rolling circles, as a given link system the links of which have definite lengths will produce a correct rolling movement only at a definite diameter of the rolling circle 25 corresponding to the length of the links. This invention has for its object to enable a correct rolling movement of wheels the pitch or rolling circles of which may be varied within wide limits, to be obtained in such 30 machines by means of one and the same link system. The invention consists, essentially, in this that the tool is displayed relatively to the wheel blank in the direction of rolling of the latter proportionally to the 35 placement of the wheel blank in such a way that the said displacements will bear a relation to one another which corresponds to the relation the difference between the 40 radii of the rolling circles of the link system and of the wheel blank bears to the radius 45 of the rolling circle of the link system. In the preferred embodiment of the invention, the machine part carrying the tool is pivotally connected to a double-armed lever 50 of which one end is provided with a stationary guide way, the other end of said lever being controlled by the machine part carrying the wheel blank, the axis of rotation of the said lever being situated on a tangent

to the rolling circle of the wheel blank which is parallel to the direction of rolling.

The invention is illustrated in the accompanying drawings, Fig. 1 shows diagrammatically a known link system. Fig. 2 shows diagrammatically one embodiment of a link system according to this invention. Fig. 3 is a top plan view of a machine for manufacturing spur gear wheels and having a link system according to Fig. 2. Fig. 4 is a side elevation of the machine, as shown in Fig. 3, partly in section.

The known link system illustrated in Fig. 1 by means of which the cylinder C is caused to roll on the plane surface P, consists of a link or crank *a* rigidly connected to the shaft *x* of the cylinder and having a length equal to the radius of the cylinder C. Pivotally and slidably connected to the free end *a*, of said link *a* is a link *b* having a shaft *x*₁ stationary with relation to the shaft *x* and being pivotally and slidably guided at the point O where the rolling movement of the cylinder C begins. The shaft *x*₁ of the link *b* is always situated on the straight line L extending through the rolling point *o* at every instant and through the cylinder shaft *x*. The two shafts *x* and *x*₁ may be attached to a slide movable in the direction of rolling and the displacement of which causes the cylinder C by the aid of the link system *a*, *b* to move relatively to the plane surface P. It should be understood that the character of this movement depends on the length of the link *b*, and by choosing this length, as proposed, equal or approximately equal to thrice the radius of the cylinder C, the said movement will represent, for small angles of rolling, a practically, ideal rolling movement on the plane surface P. The link system shown cannot, as is readily understood be used for unrolling other cylinders than those having their radii equal to the length of the link *a*.

In Fig. 2 there is shown an arrangement of the link system according to this invention whereby one and the same link system may be used for unrolling cylinders having different radii. The link system proper is identical with that shown in Fig. 1, and consists of the two links *a* and *b*. When the slide carrying the shafts *x* and *x*₁ is displaced in the direction of rolling by a distance O—*o* the cylinder C will move, as

above described, by a corresponding distance while rolling on the plane surface P . Assuming now another cylinder C_1 coaxial with the cylinder C and rigidly connected thereto and having a diameter which is less than that of the cylinder C , it is readily understood, that said other cylinder in the said displacement of the shafts x and x_1 will move along a plane surface P_1 parallel to the surface P by a distance equal to the distance $O-o$. The cylinders C and C_1 having different radii, the movement of the cylinder C_1 on the surface P_1 cannot, as was the case with the movement of the cylinder C on the surface P , be a proper rolling movement but will be, in part, a displacement and, in part, a rolling movement. The rolling movement, as is readily understood, will take place along a portion of the surface P_1 bearing a relation to the distance $O-o$ on the surface P which is equal to the relation which the radius of the cylinder C_1 bears to the radius of the cylinder C . Rolling movement, in other words, will take place along a distance corresponding to the distance O_1-o_1 , while the distance O_1-o_2 represents the portion of the total distance O_1-o_1 on which sliding movement takes place. Thus, by displacing the surface P_1 in the direction of rolling by a distance O_1-o_2 while at the same time moving the cylinder C_1 by the distance O_1-o_2 , the movement of the cylinder C relatively to the surface P_1 will be a proper rolling movement by a distance equal to the distance O_1-o_2 . The length of the distance O_1-o_2 representing the displacement bears a relation to the total length O_1-o_1 which is equal to the relation which the difference between the radii of the cylinders C and C_1 bears to the radius of the cylinder C . The said displacement of the surface P_1 may be effected according to this invention by pivotally connecting to the surface P_1 as at o_2 , indicated in the drawing by the dotted line, a double-armed lever c of which one end is provided with a stationary guide-way at the initial point O the other end of said lever being guided by the movable shaft x of the cylinder C . The said lever in the movement of the cylinder C_1 from the initial position O_1 and to the position o_1 will evidently displace the surface P_1 accurately by the distance O_1-o_2 , and rolling will take place by means of the links a and b by a distance corresponding to the distance O_2-o_1 . Evidently, the lever c need not be guided necessarily at the points O , o_2 and x , but may be substituted by any lever situated any-where and parallel to the lever c , as for instance the lever c_1 indicated by full lines in the drawing. An essential requirement is only that the axis of rotation o_2 of the lever is situated on a tangent to the cylinder C_1 parallel to the direction of rolling. By placing the surface of rolling P_1 on a slide

adjustable at right angles to the direction of rolling and by means of which the axis of rotation o_2 may be adjusted in the said direction so that the distance o_1-x becomes equal to the radius of rolling desired, it is possible, by means of one and the same link system (a , b) to unroll cylinders having radii of any desired length.

In Figs 3 and 4 there is shown a constructional form of the link system according to Fig. 2 as applied to a machine for manufacturing spur gear wheels. Like reference numerals for the sake of clearness have been used, as far as possible, to indicate corresponding parts in Figs. 2, 3 and 4. With reference to Figs. 3 and 4, 1 denotes a frame carrying a slide 2 movable in the direction of rolling and forming a bearing for the shaft x of the link a as well as for the shaft x_1 of the link b . The link b is provided at its one end with a pivot O mounted in a bearing 3 formed in the frame 1, and forms at the same end a guide-way or seat 4 for a slide 5 carrying the pivot a_1 of the link or crank a , connected at its other end to the shaft x . Provided at the other end of the link b is a guide-way or seat 6 for a slide 7 carrying the shaft x_1 so that upon the displacement of the slide 2 and the resulting swinging movement of the link b about the rigid pivot O , the shaft x_1 with the slide 7 may be displaced relatively to the link b . Rigidly connected to the shaft x of the link a is a table 8 for receiving the wheel blank H to be rolled relatively to the tool by means of the link system. The tool consists in this case of a vertically adjustable cutter 9 representing one tooth of an imagined generating rack on the pitch surface P_1 of which the wheel blank H is to be rolled with its pitch circle C_1 . The cutter 9 is carried by a slide 10 movable in the direction of rolling and journaled, as by means of an arm 11 and a pivot o_2 , to the double armed lever c_1 . The lever c_1 , the geometric axis of rotation o_2 of which is shown as adjusted into the surface P_1 touching the pitch circle C_1 of the wheel blank H , is shaped to form guide-ways both for a slide 12 supporting a pivot pin or shaft 13 journaled in the machine frame 1, and for a slide 14 having attached to it a pivot pin or a shaft 15 journaled in an arm 16 projecting from the slide 2. The slide 10 is carried by a slide 17 guided in the frame 1 and adjustable at right angles to the direction of rolling so as to enable the pivot pin o_2 of the lever c_1 which is connected to the slide 10 to be adjusted according to the rolling or pitch circle in each instance.

The operation of the device corresponds in all essential parts to that described in connection with Fig. 2 and is briefly stated as follows. The wheel blank H having been clamped to the table 8, and the tool 9 with the pivot pin o_2 of the lever c_1 having been

adjusted correspondingly to the pitch circle C_1 of the wheel blank, the tool 9 is caused, as by means of any appropriate driving means, to perform a reciprocating cutting movement, the slide 2 being at the same time displaced slowly in the direction towards the tool (that is downwards in Fig. 3). This will produce, by means of the lever c_1 , a displacement of the slide 10 with the cutting tool 9 in the direction of movement of the slide 2 so that, as explained in connection with the description of Fig. 2, the relative movement of the wheel blank with respect to the tool will be a pure rolling movement and the tool will form a complete tooth space in the wheel blank. As will appear from Fig. 3 the unrolling operation takes place at both sides of the central position of the link system and, preferably, symmetrically with respect to said position thus ensuring a more correct tooth shape than would be obtained in case of the unrolling taking place at one side of the central position only.

It should be understood that while one embodiment of the invention is shown in the accompanying drawings by way of example, the invention may be embodied in other forms and that the details of the embodiment shown may be variously changed and modified without departing from the spirit of the invention, which is not limited to any particular form or construction of the parts except in so far as such limitations are specified in the claims.

What I claim is:

1. In a machine for manufacturing gear wheels according to the principle set forth, the combination with a link system for producing a relative rolling movement between a wheel blank and a tool, of means for displacing the tool relatively to the wheel blank in the direction of rolling of the latter proportionally to the displacement of the wheel blank in such a way that said displacements will bear a relation to one another corresponding to the relation which

the difference between the radii of the rolling circles of the link system and of the wheel blank, respectively, bears to the radius 50 of the rolling circle of link system.

2. In a machine for manufacturing gear wheels on the principle set forth, the combination with a link system for producing a relative rolling movement between a wheel 55 blank and a tool, of means for carrying the tool, means for carrying the wheel blank, a double-armed lever, a pivotal connection between said lever and the means carrying the tool, a stationary guide for one end of 60 said lever, the other end of said lever being controlled by the means carrying the wheel blank, the said pivotal connection being situated on a tangent to the rolling circle of the wheel blank parallel to the direction 65 of rolling.

3. In a machine for manufacturing gear wheels according to the principle set forth, the combination with a link system for producing a relative rolling movement between a wheel blank and a tool, of means 70 carrying the tool, said means being adjustable in a direction at right angles to the direction of rolling.

4. In a machine for manufacturing gear 75 wheels according to the principle set forth, the combination with a link system for producing a relative rolling movement between a wheel blank and a tool, of means 80 for carrying the tool, said means being adjustable in a direction at right angles to the direction of rolling, means for carrying the wheel blank, a double-armed lever, a pivotal connection between said lever and the means carrying the tool, a stationary 85 guide for one end of said lever, the other end of said lever being controlled by the means carrying the wheel blank, the said pivotal connection being situated on a tangent to the rolling circle of the wheel blank 90 parallel to the direction of rolling.

In testimony whereof I have signed my name.

SVEN GUSTAF WINGQUIST.
